UNITED STATES PATENT OFFICE

158,982

COMBINED CLOCK AND RADIO

Henry G. Lewand, Philadelphia, Pa., assignor to
Philco Corporation, Philadelphia, Pa., a corporation of Pennsylvania

Application March 4, 1949, Serial No. 1,222

Term of patent 7 years

(Cl. D56—4)

To all whom it may concern:

Be it known that I, Henry G. Lewand, a citizen of the United States, residing at Philadelphia, in the county of Philadelphia and the State of Pennsylvania, have invented a new, original, and ornamental Design for Combined Clock and Radio, of which the following is a specification, reference being had to the accompanying drawing, forming part thereof, and in which:

Figure 1 is a perspective view of a combined clock and radio showing my new design;

Figure 2 is a front elevational view of the same; and

Figure 3 is a top plan view of the same.

The side of the cabinet not illustrated in the drawing is substantially similar to the side shown.

I claim:

The ornamental design for a combined clock and radio, substantially as shown and described.

HENRY G. LEWAND.
